HAT BRIM IRONING MACHINE

Rudolph G. Segschneider, Yonkers, N. Y.

Application November 25, 1931
Serial No. 577,206

11 Claims. (Cl. 223—28)

My present invention relates to improvements in the construction and mode of operation of machines for ironing the brims of hats.

The general object of my invention is the provision of a hat brim ironing machine which is characterized by its simplicity and low cost of construction and its high operating efficiency. A further and more specific object is the provision of a machine of the character described in which hats of various brim sizes and shapes may be treated without requiring any change in the arrangement of the parts or adjustment of the operating mechanism. Another object is the provision of a machine of the character described in which the brim is given a glazing treatment immediately after the ironing operation. Another object is the provision of a machine of the character described which obviates the use of special crown block constructions and supporting mechanism therefor.

The various features of novelty which characterize my invention are pointed out with particularity in the claims annexed to and forming a part of this specification. For a better understanding of the invention, however, and the advantages possessed by it, reference should be had to the accompanying drawing and descriptive matter in which I have illustrated and described a preferred embodiment of the invention.

30 Of the drawing:

Fig. 1 is a plan view of a hat brim ironing machine constructed in accordance with my invention;

Fig. 2 is an elevation of the machine shown in Fig. 1; and

Figs. 3 and 4 are sectional views on the lines 3—3 and 4—4, respectively, of Fig. 1.

In the drawing a machine embodying my invention is illustrated as supported upon a suitable platform or bed A. The machine comprises a table B of general rectangular formation having legs B' adjacent to its corner portions for supporting the table at a suitable level above the bed A. A hat C, the brim C' of which is to be ironed, is shown as resting on the table in an upright position with the lower surface of its brim in contact with the flat upper surface of the table. The brim of the hat is adapted to pass between the adjacent flat surfaces of substantially vertically aligned upper and lower heated irons D and E, respectively, whereby corresponding portions of the upper and lower brim surfaces will be simultaneously treated.

The upper iron D consists of an elongated rectangular box-like member D' having an opening

D² in its rear wall of sufficient size to permit the passage therethrough of a fuel nozzle F for discharging a combustible gaseous fuel mixture into the interior of the iron, and yet permitting small vertical bodily movements of the member D' relative to the nozzle. The opening D² also serves as an exit for the products of combustion from the iron and for the passage of fuel ignition means. Obviously, the irons may be heated electrically instead of by fuel gas. The iron D is secured to the forward end of a flat flexible bar D⁴, which is fulcrumed on an inverted U-shaped bracket D⁵ secured to the table below an intermediate portion of the bar. The rear end of the bar D⁴ is connected through a vertical link or cord D⁶ to a treadle (not shown), which is adapted to be actuated by the machine operator to raise the iron D sufficiently to permit the insertion of the hat brim. The iron D is normally held against the lower iron by a helical spring D⁷ pressing down on the bar D⁴ and by gravity. A thumb screw D⁸ extends through the spring and a slot in the bar into engagement with the bracket and in operation may be used to adjust the compression of the spring D⁷. The fuel nozzle F communicates with a supply main F³ through a pipe F', in which a control valve F² is located.

The upper surface of the table B is advantageously made of metal of high thermal conductivity and light weight, such as aluminum, except the portion below and at both sides of the iron D which is an insert G formed of metal, such as brass, which is of lower heat conductivity and less liable to oxidation when heated than aluminum. The plate G and the table opening B² in which it is located are symmetrically arranged relative to the longitudinal center line of the table. Brackets B³ extending across and below the end portions of the opening B² serve to support the plate G at the same level as the adjoining sections of the table. The iron E is advantageously formed integrally with the plate G by rectangularly arranged depending plate members E' forming a recess E², below the open lower end of which is arranged a fuel burner nozzle H carried at the inner end of a fuel supply pipe H'. The latter is connected to the supply main F³ at a point subsequent to a control valve H². The upper iron D is preferably formed of the same low heat conducting metal as the lower iron E.

In operation the brim of the hat is continuously moved between and past the adjacent coacting surfaces of the irons, which transmit heat and pressure to the material forming the correspond-

ing surfaces of the brim by mechanism herein-after described.

The hat is ordinarily received at the brim ironing machine with a wooden crown block C² in place therein. The block may be of any form heretofore used in hat blocking operations provided the bottom surface thereof does not extend below the lower surface of the hat brim. The hat with such a block inserted therein is 10 placed on the table and the upper iron raised to permit a portion of the brim to be inserted between the irons and then given a bodily movement through an elliptical path on the table to pass successive sections of the oval-shaped brim 15 between the irons.

The mechanism for moving the hat relative to the irons comprises a pair of elongated rolls J and K arranged respectively alongside the upper and lower irons and in the vertical plane of the 20 longitudinal center line of the table to provide a roll pass at the same level as the passage between the irons, as shown in Fig. 4. The upper roll J is of frusto-conical form and is arranged with the lowermost portion of its periphery in a horizontal plane and having a frictional contact with the upper brim surface. The tapered end of the roll J extends to a point adjacent the inner edge of the brim. The roll is mounted on an inclined shaft J', which extends rearwardly of the machine and is journaled in two axially spaced inclined bearings J² and J³, which maintain the roll J in the position described. The lower roll K is of cylindrical form and is mounted on a horizontal shaft K', which has its inner and 30 outer end portions journaled in bearings K² and K³. The upper peripheral portion of the roll K is arranged in a recess G' formed in the plate G alongside the portion thereof forming the lower iron E. The upper part of the periphery of the roll K is at the same level as the upper surface of the plate G and frictionally engages the lower 40 surface of the hat brim in operation. A collar K⁴ on the shaft K' and movable in a slot G² of the plate G prevents axial displacement of the roll K.

The roll driving mechanism comprises a power shaft L rotated by a suitable source of power (not shown) through a pulley L'. The power shaft L extends parallel to the rear end of the table 50 with its end portions journaled in projecting bearings L². A worm L³ is carried on the shaft at an intermediate point thereon and forms with a worm wheel L⁴ a driving connection with the roll shaft K'. The drive shaft J' for the upper 55 roll is driven from the shaft K' through spur gears L⁵ and L⁶, as shown in Figs. 1 and 3, at a speed substantially higher than that of the shaft K'. The upper iron is formed with a laterally 60 projecting and depending section D⁹ which is co-extensive with the upper roll J and protects the latter from dust and other deposits which would cause discoloration of the hat portions contacting therewith. In operation the rolls J and K engage the portions of the brim immediately after 65 passing between the irons and by their rotation, arrangement and proportions subject the hat to a continuous uniform driving effect.

The provision of a pair of smooth surfaced rolls 70 rotating at different angular speeds at the point at which the freshly ironed portions of the hat brim emerge from the irons causes both upper and lower surfaces of the brim to have a slipping contact with the roll surfaces while in a heated condition and due to which the brim material receives a desirable glossy finish.

To avoid the necessity of an operator being in constant attendance on the machine for the purpose of guiding the movement of the hat relative to the irons and glazing rolls, I have provided a pair of hat guide members which simulate the proper arrangement and action of the operator's hands. As shown in Fig. 1, a guide plate M having a curved inner surface is positioned at a point adjacent but subsequent to the rolls J and K and arranged to contact with the lower side of the crown when the hat is in position for operation. The guide M is formed with a horizontally projecting tongue M' which is pivotally connected to a horizontally arranged arm M² to permit limiting oscillating movements of the guide M relative to the arm M². The arm M² is normally arranged in a horizontal plane as shown, but is movable vertically to raise the guide M out of position by means of a pivotal connection with a stud M³ carried by a table bracket M⁴. The second guide member is arranged to engage the side of the hat crown directly opposite the roll pass and is formed by a resilient bar N, which when in its operative position bears lightly against the lower side portion of the crown. The 100 opposite end of the guide member N is pivotally mounted on a bracket N' through a stud N², permitting the guide to be raised to a vertical position.

In the operation of the machine, the irons are 105 heated to the proper temperature and the fuel control valves adjusted so that this temperature will be maintained. The guide member M and N are raised to their vertical positions. The operator then arranges the hat with its crown block 110 in position on the table and raises the upper iron to permit a portion of the brim to be inserted between the irons. The guide members M and N are then moved to their operating positions and the rolls J and K put into operation. The hat, 115 which is usually of the oval shape illustrated in the drawing, will be progressively and continuously advanced past the ironing point by the action of the rolls J and K. In the machine 120 illustrated, the hat brim is arranged to move in a counter-clockwise direction over the table and the rolls J and K are therefore rotated in a counter-clockwise and clockwise direction, respectively, as viewed from the rear of the machine. As each portion of the brim passes between the 125 irons, the material on both sides thereof is subjected to heat and pressure and the felt fibers will be uniformly pressed flat throughout the brim width. The ironed portion of the brim then moves through the roll pass between the 130 rollers J and K and receives a glazing treatment on both of its surfaces. The hat will continue to be rotated until all portions of the brim have undergone the ironing and glazing treatment 135 described, due to the action of the guide members M and N, which coact to prevent the brim from being moved out of its proper position relative to the irons and rolls. When all portions of the brim have been treated, the guide members M and N are raised and the hat then passes out of 140 engagement with the rollers.

While in accordance with the provisions of the statutes, I have illustrated and described the best embodiment of my invention now known 145 to me, it will be apparent to those skilled in the art that changes may be made in the form of the apparatus disclosed without departing from the spirit of my invention as set forth in the appended claims, and that certain features of my invention 150

may sometimes be used to advantage without a corresponding use of other features.

Having now described my invention, what I claim as new and desire to secure by Letters

5 Patent is:

1. A hat brim ironing machine comprising in combination, a supporting table adapted to support a hat resting thereon in an upright position and freely movable over the table with substantially the entire lower surface of its brim in contact therewith, a heated iron arranged to contact with the upper surface of said brim and to press said brim against said table and means acting on said brim for advancing successive portions of said brim past said iron.

10 2. A hat brim ironing machine comprising in combination, a supporting table adapted to support a hat resting thereon in an upright position and freely movable over the table with substantially the entire lower surface of its brim in contact therewith, a heated iron arranged to contact with the upper surface of said brim and to press said brim against said table, means acting on said brim to rotate said hat and to continuously advance successive portions of said brim past said iron, and means for guiding the hat during said movements.

15 3. A hat brim ironing machine comprising in combination, a table for supporting a hat in an upright position with substantially the entire lower surface of the brim in contact with said table and on which said hat is freely movable in operation, means for ironing the brim of said hat so supported, and means for advancing said brim past said ironing means including a pair of rolls arranged to form a horizontal roll pass and to frictionally contact with said hat brim.

20 4. A hat brim ironing machine comprising in combination, a table for supporting a hat in an upright position with substantially the entire lower surface of the brim in contact with said table and on which said hat is freely movable in operation, means for ironing the brim of said hat so supported, and means for advancing successive portions of said brim past said ironing means including a pair of rolls arranged to frictionally contact with opposite surfaces of said hat brim, means for driving said rolls, one of said rolls being tapered and located above the level 25 of said table, and the other of said rolls being arranged in an opening formed in said table and directly below said other roll.

25 5. A hat brim ironing machine comprising in combination, a supporting table adapted to support a hat resting thereon in an upright position and freely movable over the table with substantially the entire lower surface of the brim in contact with said table and having a heated surface portion over which the lower surface of the brim of said hat is movable in operation, a heated iron arranged to contact with the upper surface of said brim and to press said brim against said heated table surface, upper and lower rolls having a frictional contact with the corresponding surfaces of said brim and arranged to advance successive portions of said brim past said iron, and guide members contacting with the crown of said hat and coacting to prevent said brim from passing out of engagement with said rolls.

30 6. A hat brim ironing machine comprising in combination, a supporting table adapted to sup-

port a hat resting thereon in an upright position and freely movable over the table with substantially the entire lower surface of the brim in contact with said table and having a heated surface portion over which the lower surface of the brim of said hat is movable in operation, a heated iron arranged to contact with the upper surface of said brim and to press said brim against said heated table surface, means acting on said brim for advancing successive portions of said brim past said iron, and means for raising said iron to permit said brim to be positioned thereunder.

35 7. A hat brim ironing machine comprising in combination, a supporting table adapted to support a hat resting thereon in an upright position and freely movable over the table and having a heated surface portion formed of material having a lower thermal conductivity than the surrounding portions of said table and over which the lower surface of the brim of said hat is movable in operation, a heated iron arranged to contact with the upper surface of said brim and to press said brim against said heated table surface, and means for advancing successive portions of said brim past said iron.

40 8. A machine of the character described comprising in combination, means for supporting a hat in an upright position and on which said hat is relatively movable in operation, upper and lower glazing rolls arranged to frictionally contact with the corresponding surfaces of the brim of said hat, and means for rotating one of said rolls at a higher speed than the other.

45 9. A machine of the character described comprising in combination, means for supporting a hat in an upright position and on which said hat is freely movable in operation, a pair of rolls arranged to form a horizontal roll pass through which the brim of said hat is arranged to pass with said rolls in frictional contact with the opposite surfaces of said brim, and means for rotating one of said rolls at a higher speed than the other.

50 10. A hat brim ironing machine comprising in combination, means for supporting a hat in an upright position and on which said hat is relatively movable in operation, means for ironing the brim of said hat, a pair of rolls arranged to frictionally contact with said hat brim, and means for rotating one of said rolls at a higher speed than the other.

55 11. A hat brim ironing machine comprising in combination, a supporting table adapted to support a hat with a crown block therein in an upright position and freely movable over the table with its brim in contact with the table, ironing means adapted to act on the brim of a hat so supported, a pair of feed rollers providing a brim receiving roll pass approximately at the table level and adjacent, and adapted to draw the hat brim past said ironing means, one of said rolls being conical and having its smaller end adjacent the crown of the hat whereby the rolls give the hat a rotative movement on the table, a guide engaging the hat crown at the side of the latter adjacent said rolls, means yieldingly engaging the crown of the hat at the side thereof remote from, and pressing the hat toward said ironing means.
